[57] **CLAIM**

The ornamental design for a pair of elliptical tubes for hitch receiver, as shown and described.

DESCRIPTION

FIG. 1 is a perspective view of the pair of elliptical tubes for hitch receiver of the present invention;

FIG. 2 is a rear elevational view thereof;

FIG. 3 is a right side elevational view thereof;

FIG. 4 is a front elevational view thereof;

FIG. 5 is a left side elevational view thereof;

FIG. 6 is a top plan view thereof; and,

FIG. 7 is a bottom plan view thereof.

The showing of the mounting brackets and receiver box in phantom is for illustrative purposes only, and forms no part of the claimed design.
